PORTABLE MANUALLY OPERABLE PLATING DEVICE

Jean Jacques Georges Icxi, 29 Rue Dareau,
Paris, France

Filed Nov. 19, 1952, Ser. No. 321,327

Claims priority, application France Mar. 23, 1948

11 Claims. (Cl. 204—224)

The present invention relates to apparatus for electro-plating and is more particularly concerned with portable manually operated apparatus for applying the electrolyte and a positive source of electrical current to the surfaces to be plated. The present application is a continuation in part of my co-pending U.S. application Serial No. 82,263, filed March 18, 1949, now abandoned.

In the method of electroplating employing the present apparatus, the electrolyte containing a salt of the metal to be plated out is absorbed by an element of the apparatus which is then applied to the surface to be plated without the necessity of immersing the surface being treated in a plating bath. The negative terminal of a source of plating current is attached to the treated surface and the positive terminal is attached to an anode carried by the plating apparatus and in contact with the absorbed electrolyte. The electrical current therefore passes through the electrolyte between the anode and the negative surface, causing the metal to be deposited on said surface.

The principal object of the present invention is to provide a portable manually operable plating device that is capable of industrial utilization in that it will yield in a very short time, plating coats of a thickness and quality comparable to bath plating and can be used for indefinite periods permitting extended platings to be applied in a relatively short time.

A further important object of the invention is to provide a manually operable plating device which can utilize high current densities for long periods of time in the plating operation without undue heating of the elements thereof, thereby protecting the operator and apparatus from injury or damage.

A still further and equally important object of the invention is to provide a portable plating device having substantially an unlimited supply of electrolyte for continuous and extensive plating operations.

Another object of the invention is to provide a manually operable plating device of comparatively lightweight construction and one which has all electrical conductors shielded for preventing undue strain or injury to the operator using the same.

Further and important objects of the invention will be in part pointed out and in part obvious from the following description of the accompanying drawing, in which:

Fig. 1 is a side perspective view of a portable manually operable plating device according to the present invention.

Fig. 2 is a front elevation with parts in section and broken away to show the details of the device of Fig. 1.

Fig. 3 is a longitudinal section through a modified form of plating device, and,

Fig. 4 is a longitudinal section through a further modification of a plating device according to the invention.

Referring now more in detail to the accompanying drawings, wherein like and corresponding parts are designated by similar reference characters, Figs. 1 and 2

2

show a portable manually operable plating device having a handle 1 from which extends an annular body 2. Said handle and body are made of two pieces of material and body 2 is formed with an internal cavity which is closed by a pair of circular plates 3, one on each side of said body, and fastened together by nuts and bolts 4 extending therethrough. Body 2 has a tangentially extending opening 5 through which extends a tube 6 to be connected to a source of an electrolyte. The forward end of tube 6 has a substantially perpendicularly extending closed end tube 7 having a series of perforations 8 extending therealong. Each plate 3 has a curved arm 9 and 10 respectively extending therefrom and forwardly in a direction substantially parallel with said tube 6. A tube 12 is connected to arm 10 by means of a plug 13, while arm 9 has a similar tube 11 attached thereto by a plug 14. Further, arm 9 has a threaded end upon which is mounted a connector cap 15 in threaded engagement therewith. Similarly, arm 10 has a threaded end portion upon which is screwed a connector cap 16. A pair of tubes 17 and 18 extending contiguously from the ends of said arms 9 and 10 respectively and between said tubes is mounted a roller consisting of a pair of end plates 19 mounted on and closing the opposite ends of a carbon tube 20.

Arm 9 has a longitudinal bore 21 extending therethrough, while arm 10 has a similar bore 22. A metallic tube 23 is mounted in the end of bore 21 and has a bore 24 of its own into which extends the reduced end portion 25 of an elongated cylinder 26. The main portion of cylinder 26 extends within the bore of tube 17, while the closed bottom end thereof has a threaded opening 27. Tube 17 has a flange 28 extending from the top end thereof and abutting against arm 9 and tube 23. Cap 15 has said flange 28 positioned therein and upon the tightening of said cap on arm 9, draws tube 17 tightly against the bottom end of said arm. The lower closed end of tube 17 also has a threaded opening 29 in line with opening 27 of cylinder 26.

The threaded end portion 30 of a shaft is screwed through openings 27 and 29 with opening 31 of said shaft positioned in line with a bore of cylinder 26 and thus placing the elongated passage 32 of said shaft in communication with said bore. Passage 32 extends towards the middle portion of said shaft where a plurality of radially extending openings 33 are in communication therewith.

The opposite end of said shaft has a similar passageway 34 in communication with radially extending openings 35 and the opposite threaded end 36 of said shaft extends within tube 18. Between tube 17 and one plate 19 is positioned a spacer nut 37, while a similar nut 38 is positioned between tube 18 and the other of said plates 19. Each of said plates 19 has a central bore providing a raceway for ball bearings 39 permitting said plates to freely rotate. The interior bore 40 of carbon tube 20 is in communication with said openings 33 and 35 and the periphery of tube 20 is encased in an absorbent mass 41. Further said plates 19 have reduced threaded portions 42 each screwed into a threaded end 60 of said tube 20 forming a roller therewith.

The closed end of tube 18 has a threaded opening through which extends portion 36 of said shaft and a cylinder 44 extends within the bore of said tube 18, while the reduced upper portion 45 of said cylinder extends within arm 10. Said cylinder further has an opening 46 in the closed end thereof which extends in line with opening 34 and has threaded end 36 extending therein with passageway 34 being in communication with bore 47 of said cylinder.

Tube 18 has a flange 48 positioned within cap 16 whereby said tube can be drawn against the open end of

arm 20. A metallic tube 49 is mounted within the bore 22 of arm 10 and has a bore 50 of its own into which is inserted reduced portion 45 of cylinder 44.

An electrical connecting wire 51 is fixedly connected to tube 49, while another branch 52 of the same wire is fixedly connected to tube 23. Wires 51 and 52 extend through arms 9 and 10 into body 2 and outwardly through a tube 53 for connection to a source of electrical current.

Fig. 3 shows a modified form of plating device consisting of a cylinder 60 of electrical insulating material having a threaded opening 61 in the top thereof and threaded openings 62 and 63 in one side. A connector 64 for attachment to a positive source of electrical current has a threaded end 65 inserted through said opening 61 and a lock nut 66 for fastening the same in position. A metallic cylinder 67 is mounted within the bore of cylinder 60 and has a threaded recess 68 in the base thereof in threaded engagement with connector 64. Cylinder 67 further has a cavity 69 from which extends an opening 70 into the bore 71. A threaded flange 72 extends from the open end of said cylinder 67 and has peripheral threads 73.

Threaded ends 74 and 75 of liquid tubes 76 and 79 respectively are screwed through openings 62 and 63 of cylinder 60 with tube 76 screwed into the base of cylinder 67 placing its bore 77 in communication with cavity 69, while a lock nut 78 is mounted on threaded end 74 for maintaining the position thereof. Tube 79 extends through an opening 75 of cylinder 67 with its bore 80 in communication with bore 71 and a lock nut 83 is mounted on said threaded end 81 for maintaining the position thereof.

A carbon cylinder 84 having a closed base 85 and internally threaded open end 86 is screwed on to the threads 73 of flange 72 with the bore 87 being in communication with bore 71. A mass of absorbent material 88 surrounds said carbon cylinder 84 and is detachably retained thereon by a band 89. A tube 90 extends through openings 70 and into cavity 69 and also into bores 71 and 87 just short of bottom 85 of said carbon cylinder 84.

Fig. 4 shows a third modification of the present device consisting of a cylinder 95 of electrical insulating material having a threaded top opening 96 through which extends an electrical connecting post 97 whose threaded portion 98 is screwed therethrough and has a lock nut 99 for fastening the same. Within the bore of cylinder 95 is positioned a metallic core 100 having an internally threaded recess 101 into which is screwed post 97 with a reduced extension 102 extending from its opposite side having the opposite end of a metallic cylinder 103 fastened thereto by threads 104. The base peripheral portion of cylinder 103 is threaded at 105, while a bore 106 extends longitudinally of said cylinder.

A cap 107 of an electrical insulating material has an internally threaded recess 108 receiving the threaded end 105 of said cylinder 103. The base of said recess 108 is stepped as at 109 for supporting the carbon disc 110 therein. A longitudinally extending opening 111 opens into recess 108, while the periphery of cap 107 tapers inwardly as at 112, while said opening 111 has an inwardly extending projection 113. Electrolyte absorbing material 114 is inserted within opening 111 and tends to be retained therein by projections 113.

Cylinder 95 further has a pair of threaded openings 115 and 116 formed in the side thereof through which are screwed threaded ends of tubes 117 and 118. Tube 117 also screws into a threaded opening in core 100 where its bore 120 is in communication with a bore of a tube 121 extending through an opening 122 of said core. Tube 118 is screwed through a threaded opening 123 of cylinder 103 whereby its bore 124 is in communication with bore 106 of said cylinder. Lock nuts 125 and 126 are used for fastening tubes 117, 118 in position.

In the operation of the device shown in Figs. 1 and 2, an electrolyte is forced through tube 6 and out openings 8 onto the absorbent cotton 41 for maintaining a supply of electrolyte thereon as said absorbent material is rolled over the surface to be plated. At the same time electric current of a positive nature is passed through wires 51 and 52 through metallic tubes 23 and 49 and from there through metallic cylinders 26 and 44 respectively and from there to the metallic shaft ends 30 and 36. The current then passes through the roller bearings 39 to metallic plates 19 and carbon tube 20 throughout the electrolyte in the mass 41. The surface to be plated is connected to a negative source of current completing the circuit whereby the metal in the electrolyte is deposited on said surface. Handle 1, body 2, plates 3, arms 9 and 10, caps 15 and 16 and tubes 17 and 18 are all made of an electrical insulating material and also one which will retain water therein and thereby electrically insulate the current conducting elements from outside contact. Tube 11 is connected to a source of coolant, for example water under pressure, whereby the water enters arm 9 and passes through bores 21, 24 into opening 31, passageway 32, out openings 33 into the interior 40 of the roller and back into openings 35 through passageway 34, up through bores 47, 50 and 22 and out tube 12, thus maintaining a complete and continuous charge of coolant throughout all of the elements conducting the electrical current for maintaining the same relatively cool. Tubes 11, 12 and 53 are also of an electrical insulating material.

In this manner currents of high density for example around 300 amperes can be employed for creating a plating of a thickness and quality comparable to those produced in the conventional plating bath and also in a very short time. The continuous supply of electrolyte provides for plating of substantially an unlimited area, while the relatively cool elements of the device assures its continuous operation.

In the device of Fig. 3, positive electrical current of a relatively high density is supplied to post 64 and passes from and through cylinder 67 to the carbon cylinder 84 and from there to the electrolyte containing absorbent 88. Said absorbent is moved over the surface to be plated for depositing the metal from the electrolyte thereon. The operator holds the cylinder 60 which is of an insulating material and is protected thereby. A coolant under pressure is introduced through tube 76 into cavity 69 and from there through tube 90 and back up through bores 87 and 71 and out through tube 79 thereby maintaining the electrical conducting elements in a relatively cool condition.

Similarly, the modification shown in Fig. 4 has current introduced by two posts 97 through core 100, cylinder 103 to the carbon disc 110 and from there through the electrolyte in the mass 114 for plating on the negatively charged surface therewith. Coolant under pressure is introduced through tube 117, tube 121 to bore 106 and from there out through the exhaust tube 118.

Tubes 76, 79 and 117, 118 are made of electrical insulating material which is also capable of retaining water whereby the operator can hold either cylinder 60 or 95 for operating either device.

It is to be appreciated that either of the three modifications can be readily disassembled when desired and equally as well quickly and readily reassembled, permitting the quick cleaning and repairing of either device providing an economical maintenance thereof.

The foregoing devices are capable of considerable modification and such changes thereto as come within the scope of the appended claims are deemed to be a part of the invention.

What I claim is:

1. A portable manually operable plating device comprising a body of electrical insulating material providing a handle and having a pair of forwardly extending tubular arms, electrical conducting members mounted in each

of said arms and each having a passageway provided therethrough, a shaft of current conducting material connected to and extending between said conducting members and having passageways in communication with said conducting member passageways, a current conducting roller rotatably mounted on said shaft, absorbent material mounted on said roller for holding the plating electrolyte, means for connecting said conducting members to a source of electrical current and a pair of tubes each connected to one of said arms for connecting same to a supply of a coolant under pressure.

2. A portable manually operable plating device comprising a pair of tubular members of electrical insulating material, a hollow body connecting said members in substantially parallel spaced relationship and providing a handle for the operator, means for conducting electrical current extending through said body and said members and having passageways therethrough, a shaft connecting said conducting means in each tubular member and extending between the ends of said tubular members, said shaft having passageways communicating with said conducting means passageways, a roller rotatably mounted on said shaft, an absorbent material surrounding said roller, means for supplying a coolant under pressure to one arm and withdrawing it from the other of said arms after travelling through one arm, said conducting means passageways, said shaft passageways and through said other arm.

3. A portable manually operable plating device comprising a body of electrical insulating material providing a handle, a pair of tubular arms extending from said body, means for conducting electrical current mounted in each arm, a shaft extending between said arms and connected at each end to said conducting means, a hollow roller rotatably mounted on said shaft, an absorbent material mounted on said roller, said arms, conducting means, shaft and roller having communicating passageways provided therein, a pair of tubes each connected to one of said arms for supplying and withdrawing a coolant therefrom, a tube mounted on said body for being connected to a supply of an electrolyte, said electrolyte tube having an end thereof extending longitudinally of said roller with outlets directed to said absorbent material and means for attachment to a source of electrical current extending through said body and arms and connected to said conducting means.

4. A portable manually operable plating device comprising a hollow body of electrical insulating material and having a handle extending therefrom, a pair of tubular arms extending from said body, a pair of tubular electrical conductors each mounted in an end of one of said arms, a pair of cylindrical insulators, a pair of cylindrical electrical conductors each mounted within one of said cylindrical insulators and having an extension detachably inserted in the bore of one of said tubular conductors, means for detachably connecting each of said cylindrical insulators end to end with one of said arms, each cylindrical insulator having a threaded opening in its side, each cylindrical conductor having a threaded opening in its side in alignment with said insulator opening, a shaft having threaded end portions each inserted into and engaging one of said aligned insulator and conductor openings, said shaft having longitudinal and radial openings formed therein in communication with the bore of said conductors, a hollow roller rotatably mounted on said shaft, an absorbent material mounted on said roller, means mounted on said body for supplying a stream of electrolyte to said material, means extending through said body and arms capable of being connected at one end to a source of electrical current and connected at the other end to said tubular conductors and a pair of tubes each connected to one of said arms with one of said tubes capable of being connected to a source of coolant under pressure.

5. A portable manually operable plating device as

claimed in claim 7 wherein said roller consists of a pair of annular plates each having a threaded peripheral portion and a central opening through which extends said shaft, a tubular anode with internally threaded end portions receiving said plate threaded portions therein and a pair of nuts each mounted on said shaft and positioned between one of said plates and one of said cylindrical insulators.

6. A portable manually operable plating device comprising a cylindrical handle of electrical insulating material and having an opening in the head thereof, a cylindrical member of current conducting material extending within the bore of said handle and having a threaded peripheral end portion, a threaded connector post extending from the head of said cylindrical member through said handle head opening, a nut in threaded engagement with said post retaining said handle thereon, a cylindrical anode having an internally threaded open end in threaded engagement with the threaded peripheral end of said cylindrical member, said handle and said cylindrical member having a pair of aligned side openings, a pair of tubes each extending through one of said aligned openings and one tube being an inlet tube capable of connection to a source of coolant under pressure, a tube connected to said inlet tube and extending through the bore of said cylindrical member and partially into the bore of said anode and an absorbent material mounted around the periphery of said anode.

7. A portable manually operable plating device comprising a cylindrical handle of electrical insulating material having an opening in the base thereof, an elongated member of current conducting material extending within the bore of said handle and having a central cavity provided therein, said member having a threaded peripheral end portion, a disc anode positioned against the bottom of said member, a tubular cap having internal threads in threaded engagement with said member with said anode therebetween, an absorbent material extending into the bore of said cap and in contact with said anode, a threaded connector post extending from said member through said handle opening, a nut mounted on said post retaining said handle thereto, said handle and said member having a pair of aligned side openings, a pair of tubes each extending through one of said aligned openings and one tube being an inlet tube capable of connection to a source of a coolant and a tube connected to said inlet tube and extending within the cavity in said member.

8. A portable manually operable plating device comprising a cylindrical handle of electrical insulating material having an opening provided in the bottom thereof and a pair of side openings, a plug of current conducting material having a threaded passageway extending from one side to the bottom thereof and a threaded extension of reduced size, a cylindrical elongated conductor having a threaded side opening with the mouth of the bore thereof being threaded and receiving said plug extension therein, said conductor having a threaded peripheral bottom portion extending from said handle, a cylindrical cap of electrical insulating material having an opening in the base thereof and internal threads in threaded engagement with said conductor bottom portion for retaining said cap on and covering said conductor, a disc anode positioned between said cap and said conductor, an absorbent material inserted through said cap opening and being in contact with said anode, a tube connected to said plug passageway and extending within the bore of said conductor, a coolant inlet tube with threaded end portion extending through one of said handle side openings and in threaded engagement with said plug passageway and a coolant outlet tube with threaded end portion extending through the other of said handle side openings and in threaded engagement with said conductor side openings.

9. A portable manually operable plating device com-

prising a hollow open end handle of electrical insulating material to be manually supported in operating said device, at least one electrical current conducting member mounted within and extending from said handle, an electrode being connected to and in current receiving and heat transferring connection with said current conducting member, an absorbent material in contact with said electrode and capable of retaining an electrolyte received independently and exteriorly thereof for applying said electrolyte to a surface when contacting the same and depositing a plating thereon with passage of electrical current therethrough, said current conducting member having passageways therein for the passage of a coolant capable of transferring heat from said electrode as well as said member and maintaining the same relatively cool, means for conducting the coolant through said handle into and from said member passageways and current conducting means extending through said handle connected to said conducting member and capable of connection to a source of electrical current.

10. A portable manually operable plating device comprising a hollow open end handle of electrical insulating material of a configuration for being manually supported in operating said device, at least one electrical current conducting member extending within and from said handle, a liquid retaining electrode being in current receiving connection with said members and having a passageway formed therein, said member having passageways provided therein and being in communication with said electrode passageway, means for conducting a coolant through said handle into and from said member passageways, means extending through said handle for connecting said member to a source of electrical current and an absorbent material in contact with and mounted on said electrode and arranged for receiving an electrolyte independently and exteriorly thereof whereby a plating can be deposited on an electrical conducting surface by moving said material across the same with electrical current passing therethrough.

11. A portable manually operable plating device comprising a cylindrical handle of electrical insulating material capable of being manually supported in the use of said device, an electrical current conducting member positioned within the bore of and extending from said handle and having passageways provided for the passage of coolant therein, a plurality of tubes extending through said handle and each extending into one of said member passageways for conducting a coolant to, through and from said member passageways, an electrode connected to said member exteriorly of said handle for receiving current therefrom and being cooled when a coolant passes through said passageways, an electrolyte retaining material being in contact with and connected to said electrode for depositing a plating on an electrical conducting surface upon contacting the same with electrical current passing therethrough and means connecting said members to said handle and capable of being connected to a source of electrical current.
